UNITED STATES PATENT OFFICE.

EMIL A. NELSON, OF DETROIT, MICHIGAN, ASSIGNOR TO BUDD WHEEL COMPANY, OF PHILADELPHIA, PENNSYLVANIA, A CORPORATION OF PENNSYLVANIA.

DESIGN FOR A CAP NUT.

Application filed December 5, 1925. Serial No. 15,648. Term of patent 14 years.

To all whom it may concern:

Be it known that I, EMIL A. NELSON, a citizen of the United States, residing at Detroit, county of Wayne, State of Michigan, have invented a new, original, and ornamental Design for Cap Nuts, of which the following is a specification, reference being had to the accompanying drawing, forming part thereof.

Figure 1 is a perspective view of a cap nut, showing my new design.

Figure 2 is a side view of the cap nut shown in Figure 1, but with the outer and larger nut portion screwed endwise to illustrate the adjustable relation of the outer nut with respect to the central stud.

The dominant feature of the design is the hexagonal outer head having side faces with rounded corners at the inner and outer ends of the faces, together with the square central stud projecting from the central opening in said hexagonal head and having narrow flat faces at the edge portions, thus providing on the stud four large flat faces and four relatively narrow flat faces.

I claim:

The ornamental design for a cap nut, as shown and described.

In testimony whereof, I have signed my name to this specification this 28th day of November, 1925.

EMIL A. NELSON.
